Atty.

UNITED STATES PATENT OFFICE.

WILLIAM E. TAFT, OF DUNMORE, PENNSYLVANIA.

CUTTING-KNIFE.

SPECIFICATION forming part of Letters Patent No. 478,381, dated July 5, 1892.

Application filed May 8, 1891. Serial No. 392,056. (No model.)

To all whom it may concern:

Be it known that I, WILLIAM E. TAFT, a citizen of the United States of America, residing at Dunmore, in the county of Lackawanna and State of Pennsylvania, have invented certain new and useful Improvements in Cutting-Knives, of which the following is a specification.

My said invention relates to the shape of knives used in turning grooved or beaded forms, whether round or polygonal.

The object of my invention is to provide a single knife adapted to cut the bead or groove without binding or rubbing, and also to remove the wood smoothly by means of a drawing cut caused by the inclination of the edge of the knife to the axis of the revolving head and of the wood.

My invention is shown in the accompanying drawings in two different forms or as applied to two different forms of knives.

Figure 1 shows a plan view of a knife adapted to cut a circumferential groove. Fig. 2 is a transverse section on line $x\ x$ of Fig. 1. Fig. 3 shows a longitudinal section on line $y\ y$ of Fig. 1. Fig. 4 is an edge view of the knife. Fig. 5 is a plan view of a knife adapted to cut a groove circumferentially. Fig. 6 is a cross-section on line $x\ x$ of Fig. 5. Fig. 7 is an edge view of the knife. Fig. 8 is a longitudinal section on line $y\ y$, and Fig. 9 a longitudinal section on line $z\ z$.

These knives, it will be understood, are fitted to be attached to any suitable cutting-head which has rotary motion and causes the edges of the knives to move in a circular path to cut the wood arranged across the path of the revolving knives. In the form first shown in the drawings the knife is approximately semicircular in cross-section. It is intended to be clamped upon the cutting-head with the curved or convex side upward. Its edge is formed by beveling on the interior, with a full bevel at the margin, as shown at $a\ b$, Fig. 1. This causes the exterior surface of the knife to be flush with the cutting-edge of the knife at that point. The beveling diminishes from that point on each side toward the center, where it is least. The outside of the knife is beveled only about the central

part of the curve, or between the points $c\ c$, as shown in Fig. 4. It is not essential that at the central point of the edge there should be any interior bevel at all, and the bevel on the outside may at that point be full; but it is essential that the bevel at the margins or each end of the edge should be full—that is, all the bevel on the inside and the edge flush with the surface on the outside. The effect of this is that when the tool is cutting the groove by rotating against a piece of wood held within the path of its rotation the corners or those parts of the edge near the corners or ends of the edge which cut directly across the grain of the wood will pass through the groove without binding by reason of the beveling being all on the inside at that point. This is especially useful in turning polygonal forms, where the wood is moved laterally and in line with the motion of the knife and in its operation cuts through the groove repeatedly during the lateral movement of the piece which is operated upon.

In Fig. 1 the lines $e\ f$ indicate the edges of the groove and show the relation of the knife edges to the edge of the groove.

Fig. 5 and the following figures illustrate a form of knife adapted to cut a bead. In this the knife is secured to the head with the low part downward.

I have represented the form of knife adapted to cut an angular bead. In this the sloping parts of the edge $g\ h$ are flush with the interior surface of the knife and the bevel is wholly on the outside, so that as these parts pass over the bead in their rotary movement they will pass without binding. The intermediate part of the edge between the inclined part is beveled on the inside, inasmuch as it is at right angles with the plane of revolution and will not bind in any event. In this form of knife it will be observed that the position of the bevels is exactly reversed; but in both forms the bevel upon that part of the curved edge next to the ends thereof has the bevel wholly on one side, which is either the outside or inside, according as the knife edge is to cut a groove or a bead.

It will be observed in Figs. 1 and 5 that the edge is inclined to the longitudinal axis of the

knife. This is for the purpose of giving a drawing cut, which makes smoother or better work.

I claim as my invention—

- 5 1. A knife for the cutting-heads of turning-lathes, having an edge of curved or angular form, with the edge bevel on one side of the blade at the center and on the other side of the blade at the margins, as and for the purpose set forth.
- 10 2. A knife for the cutter-heads of turning-

lathes, having an edge of curved or angular form with bevels on each side, the bevels at the margin being full and the surface of the knife on the sides opposite said full bevels 15 being plain.

In testimony whereof I affix my signature in presence of two witnesses.

WILLIAM E. TAFT.
